SAFETY PLUG AND RECEPTACLE

Application filed October 26, 1935. Serial No. 64,807.

This invention relates to safety plugs and receptacles.

Objects of this invention are to provide a safety plug and receptacle for electrical translating devices such as tools, irons, toasters and the like which will lessen or prevent the danger of electric shock from the translating device although defective wiring may exist in the device.

10 A more specific object is the provision of a novel combination and arrangement of parts which will positively insure a permanent ground connection for the body of the translating device so long as the plug-receptacle connection is closed, and in which this ground connection can not be impaired or destroyed in ordinary use in the hands of a novice.

Further objects are to provide a plug and receptacle construction which is extremely simple, which does not detract from the usual appearance of these articles and which yet has the protective features discussed above.

Embodiments of the invention are shown 25 in the accompanying drawings, in which:—

Figure 1 is a sectional view of a plug and cooperating receptacle, constructed in accordance with the present invention, and showing the same applied to an outlet box.

30 Fig. 2 is a front elevation of the device shown in Fig. 1 with the plug removed and the face plate broken away for clearness.

Fig. 3 is a view similar to Fig. 1, illustrating another embodiment of the present invention with the plug displaced from the receptacle.

Fig. 4 is a front elevation of the device shown in Fig. 3 with the face plate broken away for clearness.

40 This invention contemplates providing an additional prong on the plug and an additional socket in the receptacle, together with a third wire from the additional prong, the additional prong being grounded to the translating device, and the additional socket being grounded to the casing or outlet box so that the translating device is at all times grounded while it is being supplied with current.

50 Both embodiments of the invention involve

the same type of plug. The plug shown comprises a body portion A which is equipped with a pair of prongs C, and with an auxiliary prong C'. This auxiliary prong C' is set off from the prongs C. Each of the prongs is joined or held to the body portion A by means of screws B which also join the connecting wires forming the cable D.

In the embodiment of the invention shown in Figures 3 and 4 the receptacle for co-operating with the plug A comprises a body portion F which is provided with a recessed portion F' adapted to receive the body of the plug A. This receptacle is provided with three apertures through its face, as shown in Figure 4, and back of these apertures metal contacts or prongs R and R' are positioned, as shown in Figure 3. The prongs R are arranged in pairs and the prong R' is set off to the side of the prongs R. They are each secured in place and to the connecting wires hereinafter described by means of the screws Q.

The receptacle F is locked to the cover plate L of an outlet box M by means of a spring ring H. Further, it is to be noted that the prong R' is grounded to the body of the outlet box M by means of the ground wire J, such outlet box being grounded to the conduit N which is locked thereto by means of the lock nuts P. The other prongs R are connected to the service wires or leads O.

It is to be noted that the cover plate L is held in place in the usual manner by means of screws E. Thus, when the plug is in position, one of the prongs and consequently one of the conductors in the cable D is grounded.

The embodiment of the invention illustrated in Figures 1 and 2 includes a receptacle of a somewhat different form. This receptacle has its insulating body carried by means of the outwardly projecting attaching lugs W which are apertured, as indicated, so that they may be attached to the conventional outlet box.

It is to be noted that the straps W are secured to the insulating body a by means of the screws X. This receptacle is also provided with three prongs Z and Z' similar to those

hereinabove referred to, that prongs Z' located in the lateral socket or aperture 2 being connected through a short conductor with one of the screws X and from thence to the adjacent strap W.

The receptacle a is carried within the outlet box d by means of screws L passing through the straps 11 and corresponding ears on the outlet box. This outlet box receives the usual flexible conduit f which carries the service wires, as indicated, such conduit being locked in place by means of the collar e and lock nuts, as shown.

Two of the sockets or connecting prongs Z are connected to the service wires, as shown, while the third prong Z' is grounded to the casing of the outlet box, such outlet box being grounded by means of the metal conduit f. A face plate k is held in place in the usual manner by means of screws I.

It will of course be understood that two of the wires contained in the cable D are connected with the prongs C of the plug A, respectively and with the active part of the translating device, so as to serve as a part of the power circuit therefor, while the third wire is permanently connected to the body of the translating device and with the third prong C'. Thus, when the plug is applied to the receptacle a, as in Figure 1, to complete the power circuit, the body of the translating device is automatically grounded through that third wire, prong C', contact Z', screw X, strap 11, box d and conduit f, the contact C' being automatically grounded to the outlet box upon securing the receptacle a to the box. Likewise when the plug A is applied to the receptacle F of Figure 3, the body of the translating device is automatically grounded through the prong C', contact R', lead J, outlet box M and conduit P. In both instances no external ground wire is required, the ground connections being effected through parts which are inaccessible and consequently fool proof.

Although the invention has been described in considerable detail, it is to be understood that the invention may be variously embodied and is, therefore, to be limited only as claimed.

We claim:

In a separable connection of the plug and receptacle type the combination of an outlet box, a receptacle having prong receiving sockets therein, current carrying contact members therein accessible through said sockets, an additional prong receiving socket in said receptacle, an additional contact member carried by said receptacle accessible through said additional socket, and a support for said receptacle forming an electrical connection between said additional contact member and said box to thereby effect a connection for said additional contact member

upon application of said receptacle to said box.

In testimony that we claim the foregoing we have hereunto set our hands in the county of Milwaukee and State of Wisconsin.

HALLACK T. CHANEY.
JOHN M. THOMPSON.
